SAFETY RAZOR AND BLADE SHARPENER

Albert E. Donovan, Laniel, Quebec, Canada

Application June 25, 1946, Serial No. 679,036

5. Claims. (Cl. 51—158)

1.

The present invention pertains to an improvement in shaving blade holders and sharpeners and more particularly to safety razors and razor blade sharpening devices.

The main object therefore resides in the provision of shaving and blade sharpening means of improved performance and of a character such that it is adapted to use the common Gillette-type safety razor blade.

A further object of the invention is the provision of a razor blade holder adapted to hold the blade both for shaving and sharpening purposes.

Still another object contemplates a blade sharpening device adapted to preserve and restore, after use, the same keen edge found in a razor blade when it leaves the factory.

Another object is the provision of shaving and blade sharpening means of simpler design and economical construction.

Still another object is to provide a substantially flat abrading surface for sharpening said blade, thus ensuring intimate honing contact between the entire surface of the cutting edge of the blade and said abrading surface.

Still another object contemplates a combination of the character described having a minimum of moving parts, being rugged, and having a comparatively long life.

Other objects and advantages of the present invention will become apparent or be further pointed out during the description to follow.

As an example and for purposes of illustration only, a preferred embodiment of the invention is shown in the annexed drawings, wherein

Figure 1 is a perspective view of the invention, with the razor in honing or stropping position.

Figure 2 is a partial perspective view of the combination illustrated in Figure 1, showing the razor in removed position.

Figure 3 is an enlarged detail of a vertical section taken on the line 3—3 of Figure 1.

Figure 4 is an enlarged detail of a vertical section taken on the line 4—4 of Figure 2.

Figure 5 is an enlarged detail of a vertical section taken on the line 5—5 of Figure 2.

Figure 6 is a plan horizontal partial section through the interior portion of the casing, showing the carriage with the razor removed.

Figure 7 is a general perspective view, partly in section, of the carriage side plate assembly.

Figure 8 is a perspective view of the rocking means in the carriage.

Figure 9 is a front vertical cross-section of the razor, the inner shaft being shown in perspective.

2.

Figure 10 is a composite perspective view of the razor head element in disassembled position.

Figure 11 is a partial transverse vertical section through the head of the razor and

Figure 12 shows in enlarged detail a partial perspective view of the razor guard head.

As illustrated, the combination consists in a sharpening casing generally shown at S adapted to sharpen a razor generally shown at R. Casing S is a shallow rectangular box, the side walls 10 of which are inwardly bent at the top to form lateral marginal recesses 11. A removable honing or stropping element 12 is provided at the bottom of said casing S. The longitudinal recesses 11 are adapted to receive a carriage assembly generally shown at C slidably in the bottom of said casing and coacting longitudinally with said side recesses by means to be described.

The carriage C consists in a skeleton structure having two side plates 13 and 14 facing each other and intermediately connected by cross-rods 15. Each side plate 13 and 14 is outwardly bent at the top and bottom to form U-shaped channel members 16 and 26 slidably engaging respectively, at the top, the bent portion 17 of side wall 10 and, at the bottom, a rail 18 laterally and longitudinally extending upwardly from the bottom of casing S. Each side plate 13 and 14 is furthermore provided with a pair of half circular apertures 19 diametrically opposed and adapted to receive the razor blade rocker described hereunder. Each channel member 16 is centrally cut, or milled, vertically to form a razor side-arm locating slot 29.

The razor blade rocking means is best shown in Figs. 7 and 8. Thus, outside the plates 13 and 14, a T-shaped plate indicated by T is pivotally connected centrally to each of the former. To this end, a shaft or pin 28 projects perpendicularly from the centre of each rocking member T and is rotatably and non-slidably journalled in each of the plates 13 and 14 at the virtual centres of the semi-circular apertures 19 through the latter. Between each of the plates T and the side walls 10 of the casing is disposed a curved elongated friction shoe 21, and this member will slide against the casing walls when sufficient force is applied.

The rocker T is an inverted T-shaped member provided with a pair of blade supporting rocker arms 22 extending horizontally from its base and adapted to engage apertures 19 of plates 13 and 14 and extend oscillatingly therethrough.

The rocker T is furthermore bent at the top

to form an angular finger 23 extending rearwardly therefrom.

The friction shoe 21 consists in a rectangular spring plate having at the central marginal top edge a pair of spaced right-angularly directed lugs 24 struck therefrom to provide a space for angular finger 23. The ends 64 of friction shoe 21 are slightly bent inwardly and are adapted to press on the side plates 13 and 14 of carriage C. The back portion of said shoe 21 resiliently bearing on the inner side of walls 10. The lugs 24 are adapted to receive oscillatingly in the space therebetween the bent finger 23 of rocker T and to impart a rocking motion thereto when the carriage assembly C is pulled or pushed.

The razor R consists in a razor head clamping plate 25, a secondary clamping plate 27, a blade 28, a pivoted clamping plate 29, a bracket 30, bracket side arms 31, a hollow handle 32, an inner shaft 33, and an operating knob 34 integral with shaft 33.

The clamping plate 25 is a transversely curved plate provided with end flanges 75 right-angularly directed and extending beyond the sides of said plate. Each end of the oppositely corresponding flanges 75 is joined with the other by a longitudinal comb guard 26 spaced from the side of clamping plate 25. Each flange 75 is furthermore provided centrally with a locating transverse slot 71 which engages each side-arm 31 of bracket 30. Said plate 25 thus forms a shallow arcuate body adapted to receive in its concave face the other head elements of the razor R. The plate 25 is furthermore provided on its inner surface with an internally threaded sleeve 35 right angularly projecting therefrom and adapted removably to engage co-operatively, through apertures provided centrally therein, the plate 27, the blade 28, the plate 29 and internally the hollow handle 32. On the other hand, the inner threads of said sleeve 35 are removably engaged by the threaded end of inner shaft 33.

Secondary clamping plate 27 is a rectangular member the top of which is curved transversely to fit the inner surface of plate 25 and provided on its flat-bottomed surface with at least two bayonet joints 36 and two end slots 38 adapted to engage respectively the registering apertures 37 and lugs 39 of pivoted clamping plate 29, co-acting therewith. Plate 27 is furthermore transversely apertured centrally to receive sleeve 35.

As stated before, the blade 28 is a Gillette-type blade, rectangular in shape, provided on each of its sides with a cutting edge 78 and a central longitudinal aperture 77 adapted to receive therethrough the sleeve 35 and bayonet joints 36. When the blade 28 is thus received into plate 25, the cutting edge 78 of said blade projects through the space comprised between the sides of said plate 25 and the comb guard 26, and cooperate with said sides of plate 25.

The clamping plate 29 is a rectangular member provided on its inner flat surface with at least two apertures 37 and lugs 39. When the razor is assembled, the apertures 37 are adapted to be engaged in registering assembly by bayonet joints 36 of clamping plate 27, whereas lugs 39 project through apertures 77 of razor blade and are received in registering assembly by end-slots 38 of clamping plate 27.

The ends of said plate 29 are pivotally secured to the end of side arms 31 of bracket 30 by means of short pivots 79 extending therefrom. Plate 27 is furthermore transversely apertured centrally to receive sleeve 25.

The hollow handle 32 is a tubular member open at both ends and adapted to receive rotatably into its body the inner shaft 33. The bottom end of said handle 32 being secured to the centre of bracket 30 which is also transversely apertured centrally to receive sleeve 35. Near the top of said hollow handle and projecting therein is a short lug 76.

The inner shaft 33 is threaded at its bottom end and is provided at the top with a knurled operating knob 34 having a depending flange 74 which normally rotatably rests on the circumferential edge of hollow handle 32 and thus checks the length of insertion of said inner shaft therein. Below said flange 74 the inner shaft is grooved at 72 and is adapted to engage rotatably the short lug 76 and prevent accidental extraction of the inner shaft from its container, the hollow handle 32.

The razor R is assembled by inserting the threaded sleeve 35 through the central apertures of plate 27, blade 28, plate 29 and bracket 30 and is received by inner shaft 33 to which it is screwed by means of operating knob 34, the bayonet joints of plate 27 engaging the registering apertures of plate 29.

To hone or strop the blade, the razor head clamping plate 25 is unscrewed by means of operating knob 34 and the remaining elements of the razor are inserted between the slide plates 13 and 14 of carriage C. The side arms 31 slidably engaging the slots 69 of channel members 16 and the ends of the blade 28 resting centrally on the rocker arms 22.

When the razor thus inserted is given a horizontal back and forth motion, it imparts a like-wise motion to carriage C and the blade supporting rocking arms 22 will allow alternately each side of the cutting edge of blade 28 to contact slidably the honing or stropping surface 12 of casing S, and thus will cause the blade to be sharpened.

It will be easily understood that the invention described above offers many advantages over the prior art: the razor blade does not have to be withdrawn from its holder to be honed and may be used many times before being changed for a new one; the carriage in the sharpening casing is simple and has a minimum of moving parts; the same advantages are found in the razor holder.

The present invention is accordingly considered to be an advance of the art insomuch as it effectively solves, in a manner heretofore unknown, the problem of resharpening used blades of the Gillette-type.

It must be understood that various changes as to size, shape and arrangement of parts can be effectuated without departing from the spirit of the invention or the scope of the subjoined claims.

Having thus described my invention, I claim:

1. A device of the character described comprising, in combination, a casing having an abrading element therein, a carriage frictionally-slidable longitudinally in said casing, a blade holder adapted to grip a blade pivotally, said holder removably insertable into said carriage whereby the edges of said blade are disposed transverse the casing, and means on the carriage for automatically rocking the blade to bring alternate edges thereof into contact with said element when the carriage is reciprocated longitudinally.

2. A device of the character described comprising, in combination, a casing having an abrading element therein, a blade holder, said

holder having blade-clamping means pivotally secured thereto, a carriage frictionally-slidable longitudinally in said casing adapted to removably receive said blade holder so that the edges of the blade are disposed transverse the casing, and means on the carriage for automatically rocking the blade to bring alternate edges thereof into contact with said element when the carriage is reciprocated longitudinally.

3. A device of the character described comprising, in combination, a casing having an abrading element therein, a blade holder, said holder having blade-clamping means pivotally secured thereto, a carriage frictionally-slidable longitudinally in said casing adapted to removably receive said blade holder so that the edges of the blade are disposed transverse the casing, and means on the carriage for automatically rocking the blade to bring alternate edges thereof into contact with said element when the carriage is reciprocated longitudinally, said rocking means having members adapted to abut the blade for the purpose of positively pivoting the latter.

4. The combination with a device as claimed in claim 3, of said blade holder adapted to serve as a component part of a safety razor and comprising an elongated handle and a yoked extremity, and said blade clamping means pivotally secured in said yoked extremity.

5. In a device as claimed in claim 2 said carriage and rocking means comprising: a pair of side plates slidable adjacent the longitudinal edges of said element, stays rigidly connecting said plates, a T-shaped plate pivotally connected centrally to each of said side plates having fin-

gers projecting from the lateral members thereof for the purpose of abutting the under surface of the blade, a projection on the main member of each of said T-shaped plates, a shoe disposed between each of the latter and the sides of the casing, and said shoes frictionally slidable against the casing sides and engageable with said projections, whereby said shoes drag behind the carriage during reciprocation of the latter and cause tilting of the T-shaped plates in alternate directions, and said projecting fingers transmit a corresponding tilting to the blade.
